Application March 12, 1956, Serial No. 570,934

4 Claims. (Cl. 89—1.5)

This invention relates in general to carriers and more specifically to carriers for association with aircraft or components thereof whereby an object may be releasably carried thereby and forcibly ejected therefrom.

The instant carrier is particularly adapted for use in association with a training bomb which simulates an actual bomb in size and aerodynamic contour and where it serves to releasably support a sub-calibre bomb contained within said training bomb and to eject it with a predetermined force. It is to be understood, however, that the present carrier may be utilized for other purposes, as for example to releasably carry aircraft stores such as flares, rockets and other objects that are released or dropped from the aircraft during flight.

Among other objects, the present invention contemplates a carrier embodying means whereby an object, such as a sub-calibre bomb, may be securely, yet releasably, carried by or within an aircraft or a component thereof and positively released and forcibly ejected therefrom.

With the above and other objects in view as will become apparent, this invention consists in the construction, combination and arrangement of parts, all as hereinafter more fully described, claimed and illustrated in the accompanying drawings, wherein:

Fig. 1 is a side view, partially in section, of a training bomb showing the instant carrier mounted therein and carrying a sub-calibre bomb;

Fig. 2 is a plan view of the present carrier;

Fig. 3 is a side view thereof; and

Fig. 4 is a vertical section through the carrier, taken along line 4—4 of Fig. 3.

In the training of pilots and bombardiers in aerial bombing, it has become the practice to mount a training bomb in the aircraft that is generally of the same weight and configuration as an actual bomb and which contains one or more sub-calibre bombs that are released or dropped during practice bombing runs. Among other requirements, the means by which the sub-calibre bombs are releasably mounted or carried within the training bomb must be capable of securely holding the sub-calibre bomb so that it will not be shaken loose or become disengaged from the holding means during maneuvering of the aircraft. However, the holding means must also be capable of positively and instantaneously releasing the sub-calibre bomb when it is desired so to do. In addition, it has been found desirable to impose a force on the sub-calibre bomb as it is released, i. e., forcibly eject it, in order that it will travel toward the target on a trajectory substantially similar to that of an actual bomb.

The carrier contemplated herein is so constructed and arranged that it meets all of the above requirements. In short, when utilized to releasably carry a sub-calibre bomb, the present carrier securely holds the bomb until it is to be released and at that time instantaneously and forcibly releases it.

To these ends, the instant carrier includes two pairs of complemental bomb-engaging arms that are pivotally

mounted and designed to snugly grasp a sub-calibre bomb at spaced intervals along its length. Each pair of complemental arms is connected to a toggle assembly that serves to lock them into engagement with the sub-calibre bomb. The toggle assemblies, in turn, are connected to a mechanism for simultaneously unlocking them so that the complemental arms completely release the sub-calibre bomb. In addition, the instant carrier also includes means for imposing a predetermined force upon the bomb that not only serves to hold the sub-calibre bomb in snug engagement with the arms, but also to forcibly eject it therefrom upon the unlocking of the toggles and the disengagement of the bomb-engaging arms from the bomb.

Referring to the drawings and in particular to Fig. 1, 15 10 designates a training bomb simulating the weight, size and aerodynamic characteristics of an actual bomb and adapted to be mounted on an aircraft. This training bomb 10 is hollow and provided with a pair of doors 11 that extend longitudinally along its bottom portion and 20 which are connected to any conventional mechanism for moving them between closed and opened positions, thereby permitting access to the interior of the training bomb 10. The carrier contemplated herein, and indicated generally as 12, is mounted, in a manner to be 25 more fully described, to any convenient internal structure 13 of the training bomb 10. However, the carrier 12 should be so positioned within the training bomb 10 that a sub-calibre bomb 14 may be readily engaged by or released from the carrier 12 when the doors 11 are 30 in their opened position. While only one carrier 12 has been illustrated in Fig. 1, it is to be understood that additional duplicate carriers may be mounted within the training bomb 10 the number of which depends upon its size and configuration.

35 As shown more particularly in Figs. 2, 3 and 4, the carrier 12 comprises a substantially flat rectangular base plate 15 having at each of its four corners a longitudinal extension or ear 16 that is provided with an aperture 17 for the reception of suitable securing means. Thus, 40 as shown in Fig. 1, bolts 18 are passed through the apertures 17 in the ears 16 to secure the base plate 15 of the carrier 12 to the internal structure 13 of the training bomb 10.

The base plate 15 is provided at each end thereof with a relatively thick transverse depending flange 19. 45 The ends of each flange 19 are each vertically bifurcated by a slot 20 which extends partially into the base plate 15. The slots 20 at the ends of each flange 19 are aligned transversely of the plate 15 and the corresponding slots 20 at opposite ends of the plate 15 align longitudinally thereof. Each pair of slots 20 is adapted to receive the upper portions of a pair of complemental arms 23—24. Thus, the upper portion of the complemental arm 23 is received within one slot 20, while the upper portion of the complemental arm 24 is received within the other slot 20. The complemental arms 23—24 are each mounted to the base plate 15 for limited pivotal movement within their respective slots 20 by means of a pivot pin 25 that passes through registered openings in the arm and the flange 19. The complemental arms 23—24 of each pair are provided, at the lower portions thereof, with curved or arcuate surfaces 23' and 24', respectively, that are designed to cooperate with each other to engage or embrace the sub-calibre bomb 14 when closed, i. e. when the arms are positioned substantially parallel with their lower ends adjacent. When the arms 23—24 are open, i. e. when they are angularly disposed relative to each other with the lower ends thereof spaced apart, the sub-calibre bomb 14 engaged thereby is released. For purposes that will hereinafter be set forth, the upper ends of the curved surfaces 23' and 24' are

provided with rounded cam surfaces 23" and 24", respectively.

The upper extremities of the complemental arms 23-24 of each pair are operatively interconnected by a toggle assembly 26 comprising a pair of links 27 connected together at adjacent ends by an intermediate toggle pin 28, and pivotally connected at their opposite end by a pivot pin 29, one to the upper extremity of arm 23 and the other to the upper extremity of arm 24. The toggle pin 28 of each toggle assembly 26 is engaged within a substantially L-shaped cam slot 30 formed in a cam plate 31 that is disposed between the ears or extensions 16 of the plate 15 and is pivotally mounted at its lower end by a pin 32 to the flange 19 of the base plate 15. The opposite or upper end of the cam plate 31 is pivotally joined by a pin 33 to one end of a link 34, the opposite end of which is pivotally mounted to a connecting bar 35. As best seen in Figs. 3 and 4, the connecting bar 35 serves to interconnect the links 34, and hence cam plates 30 of each toggle assembly 26, for simultaneous actuation. The connecting bar 35, in turn, is pivotally joined by a roll pin 36 to the actuating piston 37 of a solenoid assembly 38 that is mounted by bolts 39 to a lateral extension 49 of the base plate 15.

Attached to, and movable with the piston 37, is a rod 41 having an indicating button 42 mounted at its outer end that is adapted to reciprocate within an opening 43 in the wall of the training bomb 10. The rod 41 and button 42 are so constructed and arranged that when the piston 37 is disposed in one position, i. e. when the arms 23-24 engage a bomb 14, the outer surface 44 of the button 42 lies flush with the outer surface of the bomb 10, thereby indicating the closed position of the arms. On the other hand, when the piston 37 is moved in the opposite direction, the button 42 projects outwardly beyond the outer surface of the wall of the training bomb 10, thereby indicating the open position of the arms 23-24.

A torsion or clock spring 45 encircles one of the pivot pins 29 and bears at one of its ends 46 against the upper surface of the base plate 15 while its opposite end 47 is engaged under the lower edge of the associated toggle link 27. This spring 45 is effective to move the links 27 in a direction to position toggle pin 28 at the upper end of the cam slot 30, thereby breaking the toggle 26 and swinging the complemental arms 23-24 to their open position. The upper part of the cam plate moves simultaneously about pivot pin 32 from its normal vertical position.

The carrier 12 is also provided with a spring assembly 48 whereby a predetermined force or load is imposed upon the sub-calibre bomb 14 while held by the arms 23-24 and at the time of its release from these arms. Thus, the bomb is firmly held against accidental movement and may, when released by the arms 23-24, be forcibly ejected. The spring assembly 48 comprises a hollow cylinder 49 having its upper end closed by an end-wall 50 and an outstanding, substantially square flange 51 at its lower end. The end-wall 50 is provided with a centrally disposed vent or opening 52. Bolts 53 pass through registered openings in each corner of the flange 51 and the base plate 15 to securely mount the cylinder 49 in a vertical position above and on the base plate 15 and to surround an opening 54 formed through the central portion of the base plate 15. Mounted for reciprocation within the cylinder 49 and the opening 54 in the base plate 15, is a piston 55 comprising a sleeve 56 having a bottom or lower wall 57, and a piston ring 58 secured to its upper end that slidably engages the inner surfaces of the cylinder 49. A pair of concentrically disposed springs 59, positioned within the sleeve 56 of the piston 55 and operative between its end-wall 57 and the end-wall 50 of the cylinder 49 urge the piston 55 outwardly of the cylinder 49 and through the opening 54 until such movement is arrested by the engagement of

the piston ring 58 with the upper surface of the base plate 15 defining the opening 54.

A resilient pad 60, designed to conform to and engage the upper surface of the sub-calibre bomb 14, is mounted to the outer surface of the bottom wall 57 of the piston 55 by a bolt 61, the lower portion of which is formed into an indexing pin 62 that is adapted to be received within a socket 63 in the upper surface of the sub-calibre bomb 14. The engagement of the pin 62 in the socket 63 centers or aligns the sub-calibre bomb 14 between the pairs of complemental arms 23-24.

Due to the foregoing construction and arrangement of parts, the pairs of complemental arms 23-24 initially occupy their open positions, and the piston 55 is in its fully extended or downward position. To engage the sub-calibre bomb 14 with the carrier 12, the indexing pin 62 is seated in the socket 63 of the sub-calibre bomb 14 and the bomb 14 is longitudinally aligned with the pairs of arms 23-24. The upward movement of the bomb 14 between the pairs of arms 23-24 then compresses the springs 59. This movement of the bomb 14 may be accomplished manually or by any loading device depending largely upon the weight of the bomb 14 and the force exerted by the springs 59. As the bomb 14 is moved upwardly between the complemental arms 23-24, the cam surfaces 23" and 24" thereof engage and bear against the upper outer surface of the bomb 14, thereby pivoting the arms 23-24 toward the bomb and bringing their respective curved surfaces 23'-24' into engagement therewith. At the same time, the upper ends of the arms 23-24 are moved apart, thereby bringing the links 27 of each toggle assembly 26 into substantial horizontal alignment against the action of the clock or torsion springs 45. This movement of the links 27 causes the toggle pins 28 to move downwardly in their respective L-shaped cam slots 30 and, as they enter the lower or horizontal portions thereof, each cam plate 31 is moved into its normal substantially vertical position, thereby locking the links 27 in alignment, and the complemental arms 23-24 in their closed positions. As the cam plates 31 move into vertical position, the links 34 draw the connecting bar 35 away from the solenoid assembly 38 thereby projecting the piston 37 and cocking the solenoid assembly 38.

Upon the cocking of the solenoid assembly 38, its piston 37 is moved as aforesaid and the rod 41 with its indicator button 42 is also moved in the same direction until the outer surface 44 of the button rests flush with the outer surface of the wall of the training bomb 10, thereby indicating that the complemental arms 23-24 are in their closed positions and locked against pivotal movement to their open positions. At this time, the sub-calibre bomb 14 is securely engaged within the curved surfaces 23'-24' of the pairs of complemental arms 23-24 to be wholly supported by the carrier 12. Moreover, during the loading of the sub-calibre bomb 14, the springs 59 have been compressed and, as a result, they exert a force or load on the bomb 14 which acts upon the complemental arms 23-24 to pivot them apart to their open positions. However, since the toggle assemblies 26 are locked by their respective cam plates 31, such pivotal movement of the complemental arms 23-24 is prevented and the bomb 14 is securely held in position.

It is to be understood that, when the training bomb 10 is associated with an aircraft, conventional electrical circuit means and pilot-operated control means are provided to actuate the solenoid assembly 38. However, inasmuch as these electrical circuit means are purely conventional, they have neither been illustrated nor fully described. Upon the actuation of the solenoid assembly 38 to retract the piston 37, the connecting bar 35 is moved in the same direction thereby moving the upper end of each cam plate 31 out of vertical. The toggle pins 28 are then freed to move upwardly in their respective cam slots 30 under the force or load exerted through

the links 27 by the torsion springs 45 and the force or load of the springs 59 acting through the piston 55, the bomb 14 and the complemental arms 23-24. As a result, the complemental arms 23-24 are pivoted to move their curved surfaces 23'-24' away from the sub-calibre bomb 14, thereby releasing it from the carrier 12 and ejecting it therefrom under the force or load imposed thereon by the spring assembly 48. It is manifest that, by varying the strength of the springs 59, or their number, the force or load exerted thereby on the sub-calibre bomb 14 may be varied.

After the sub-calibre bomb 14 has been released as aforesaid, the torsion or clock springs 45 acting through their toggle assemblies 26 maintain the complemental arms 23-24 open. Additionally, the actuation of the solenoid assembly 38 has moved the indicator button 42 to where it is projected beyond the outer surface of the training bomb 10, thereby indicating the release of the sub-calibre bomb 14.

What is claimed is:

1. A carrier for use in a training bomb to releasably secure a sub-calibre bomb therein, said carrier comprising a base plate, a pair of complemental arms mounted at each end of said base plate for pivotal movement between closed and open positions, each pair of complemental arms having complemental curved engaging surfaces for substantially encircling the sub-calibre bomb in their closed position and complemental cam surfaces at the inner ends of the engaging surfaces operative against the outer surface of the sub-calibre bomb as it is moved toward said base plate between said complemental arms to pivot the same to their closed position to thereby engage the sub-calibre bomb, a toggle assembly associated with each of said pairs of complemental arms and operative to lock its associated pair of complemental arms in their closed position or to move them to their open position, means interconnecting said toggle assemblies for simultaneously unlocking them whereby each of said pairs of complemental arms pivots to their open position to release the sub-calibre bomb from engagement by the complemental curved engaging surfaces thereof, and means associated with said means for unlocking said toggle assemblies for indicating exteriorly of the training bomb the position of said pairs of complemental arms.

2. A carrier for releasably carrying a sub-calibre bomb within a training bomb, said carrier comprising a base plate, spaced pairs of complemental arms mounted to the opposite ends of said base plate in parallel relationship and for pivotal movement between closed and open positions, said pairs of complemental arms being adapted adjacent one end thereof to engage the sub-calibre bomb in their closed position and to release it in their open position, said pairs of complemental arms embodying means adjacent the opposite end thereof to cooperate with the sub-calibre bomb as it is moved toward the base plate to move said complemental arms to their closed position, toggle means for locking said spaced pairs of complemental arms in their closed position, resilient means carried by said base plate between said spaced pairs of complemental arms for imposing a predetermined ejecting force on the sub-calibre bomb engaged by said pairs of complemental arms, and means for unlocking said toggle locking means whereby said resilient means pivots said spaced pairs of complemental arms to their open position and the sub-calibre bomb engaged thereby is ejected therefrom under a predetermined force and along a selected trajectory.

3. A carrier for releasably carrying a sub-calibre bomb within a training bomb, said carrier comprising a base plate, a pair of complemental arms mounted at each end of said base plate for pivotal movement between open and closed positions, said pairs of complemental arms being disposed parallel one to the other and the arms of each of said pairs of complemental arms being adapted at one end thereof to engage the sub-calibre bomb when in their closed position, means adjacent the opposite end of each of said pairs of complemental arms for cooperation with the sub-calibre bomb to move the same into the closed position thereof upon the movement of the sub-calibre bomb toward the base plate between said pairs of complemental arms, a toggle assembly individual to and operatively connected with the other end of the arms of each of said pairs of complemental arms for locking them in the closed position thereof and in engagement with the sub-calibre bomb, a spring assembly carried by said base plate between said pairs of complemental arms and operative against the sub-calibre bomb engaged by said pairs of complemental arms to impose a predetermined ejecting force thereon, and means interconnecting said toggle assemblies for simultaneously unlocking the said pairs of complemental arms whereby the sub-calibre bomb is ejected therefrom under the predetermined force of said spring assembly and along a selected trajectory.

4. A carrier for releasably carrying a sub-calibre bomb within a training bomb, said carrier comprising a base plate, a pair of complemental arms mounted at each end of said base plate for pivotal movement between open and closed positions, the arms of each of said pairs of complemental arms being adapted at one end thereof to engage the sub-calibre bomb when in the closed position thereof and embodying means adjacent the opposite end thereof to cooperate with the sub-calibre bomb when it is moved between said pairs of complemental arms toward said base plate to move said pairs of complemental arms to their closed position, a toggle assembly individual to and operatively connected with the other end of the arms of each of said pairs of complemental arms for locking them in the closed position thereof and in engagement with the sub-calibre bomb, a spring assembly carried by said base plate between said pairs of complemental arms and operative against the sub-calibre bomb engaged by said pairs of complemental arms to impose a predetermined force thereon, means interconnecting said toggle assemblies for simultaneously unlocking the said pairs of complemental arms whereby the sub-calibre bomb is ejected therefrom under the predetermined force of said spring assembly and along a selected trajectory, and means for indicating exteriorly of the training bond the position of said pairs of complemental arms.
